UNITED STATES PATENT OFFICE.

WARREN W. STOLER, OF DETROIT, MICHIGAN.

VEHICLE-TOP.

1,231,962.

Specification of Letters Patent.

Patented July 3, 1917.

Application filed April 17, 1916. Serial No. 91,559.

To all whom it may concern:

Be it known that I, WARREN W. STOLER, a citizen of the United States of America, residing at Detroit, in the county of Wayne 5 and State of Michigan, have invented certain new and useful Improvements in Vehicle-Tops, of which the following is a specification, reference being had therein to the accompanying drawings.

10 This invention relates to a vehicle top, and more particularly to an arrangement of bows, bow sockets and fixtures by which a cover or canopy for an automobile may be expeditiously set up or collapsed.

15 The object of my invention is to provide an automobile top embodying comparatively few bows articulated so as to be manipulated with considerable ease when setting up the top or collapsing the same. The bows are 20 proportioned and disposed whereby the top can be set up or collapsed by one person without much exertion and in a great many instances with one hand.

Furthermore, the bows are proportioned 25 and disposed to move in a prescribed relation when setting up or collapsing the top and without injury to the material forming the cover or canopy of the automobile.

The mechanical construction by which the 30 above and other objects are attained will be hereinafter described and then claimed and reference will now be had to the drawing, in which—

Figure 1 is a side elevation of an automobile top, partly broken away, illustrating the 35 inner side of the top;

Fig. 2 is a side elevation of the top bows collapsed or folded, and

Fig. 3 is a plan of a portion of the same.

40 In the drawing, 1 denotes a portion of an automobile body having side rests 2 and side irons 3.

45 4 denotes a front bow pivotally connected to the side irons 3 and said front bow has a rear bow 5 and an intermediate bow 6. The ends of the rear bow 5 are pivotally connected to the front bow 4 contiguous to the lower ends thereof, and the intermediate bow 6 has the ends thereof pivotally connected to brackets 7 mounted upon the rear 50 edges of the front bow 4.

55 8 denotes brackets on the front edges of the front bow 4 and pivotally connected to brackets are the ends 9 of a break-down or supplemental bow 10. The ends 9 of the break down bow 10 are slotted, as at 11, ad-

jacent the break-down or rule joint 12 of the bow.

13 denotes side arms having pins extending into the slots 11 of the break-down bow 6 and the rear ends of said side arms are curved or offset, as at 15, and pivotally connected to the intermediate bow 6, adjacent the pivotal connections of said bow with the front bow. 65

16 denotes an outrigger or horizontal bow having the ends thereof pivotally connected, as at 17, to the forward ends of the arms 13, and said outrigger bow coöperates with the break-down, front, intermediate and rear 70 bow in supporting a cover or canopy 18 relative to the body 1 of the automobile.

19 denotes inwardly projecting pins or studs carried by the front bow 4. These pins or studs are adapted to retain the side 75 arms 13 a prescribed distance above the brackets 7 and 8, whereby the pivotal connections between the rear ends of the side arms 13 and the intermediate bow 6 cannot fall below the pivotal connections between 80 the brackets 7 and the intermediate bow 6, thus preventing the intermediate bow 6 from folding toward the ends of the front bow 4, particularly when folding or collapsing the top. The intermediate bow 6 is adapted to 85 fold into parallelism with the upper or outer portion of the front bow 4, as clearly shown in Fig. 2, and the offset portions 15 of the side arms 13 provide clearance for the pins or studs 19, while the slots 11 of the break- 90 down bow provide sufficient clearance to enable the side arms 13 and the ends 9 of the break-down bow to be swung downwardly in parallelism with the ends of the front bow 4, while the break-down bow and the 95 outrigger or horizontal bows are folded back as shown in Fig. 2.

The collapsing or folding of the top is easily accomplished by reason of the pins or studs 19 preventing the intermediate bow 6 100 from swinging downwardly below its pivotal connections with the front bow 4, otherwise it would be an extremely difficult matter to properly collapse or fold the top. It is therefore apparent that the pins or studs 105 19 have a very useful purpose in connection with the top and it is obvious that these same pins or studs facilitate setting up the top, which in some instances may be accomplished with one hand and very little exertion. 110

It will of course, be understood that the

bows, arms and other parts of the top are correctly proportioned for easy manipulation and comparatively small space when the top is folded, and while I have illustrated 5 one embodiment of my invention, it is to be understood that the structural elements are susceptible to such variations and modifications as fall within the scope of the appended claim.

10 What I claim is:—

An automobile top comprising a cover, a front bow, a rear bow pivotally connected thereto, an intermediate bow pivotally connected to the rear edges of said front bow, a 15 jointed bow pivotally connected to the front edges of said front bow and having the pivoted portions thereof longitudinally slotted adjacent the joint thereof, side arms having offset angular ends pivotally connected to said intermediate bow, pins car-

ried by said side arms and extending into the slots of said jointed bow, a horizontal bow pivotally connected to said side arms, and inwardly projecting stationary studs carried by said front bow above the pivots 25 of said jointed and intermediate bows adapted to support said side arms a prescribed distance from the pivotal connections of said intermediate bow with said front bow, the offset angular ends of said side arms providing clearance for said studs so that said side arms may be folded into parallelism with said front bow when said top is collapsed.

30 In testimony whereof I affix my signature in presence of two witnesses.

WARREN W. STOLER.
